CLAIM

The ornamental design for a speaker with multiple diaphragms, as shown and described.

DESCRIPTION

FIG. 1 is a top elevational view of a speaker with multiple diaphragms according to our design;

FIG. 2 is a bottom elevational view thereof;

FIG. 3 is a left side elevational view thereof, the right side elevational view thereof being a mirror image of the left side elevational view;

FIG. 4 is a front elevational view thereof, the back elevational view thereof being a mirror image of the front elevational view; and,

FIG. 5 is a bottom perspective view thereof.

The broken lines in the figures represent unclaimed subject matter and form no part of the claimed design, particularly where any broken lines immediately adjacent areas associated with surface shading represent bounds of the claimed design, while other broken lines are directed to environment and are for illustrative purposes only and form no part of the claimed design.
